UNITED STATES PATENT OFFICE.

WILLIAM H. LUTZ, OF PHILADELPHIA, PENNSYLVANIA.

RUG-ROLLING MACHINE.

1,342,556.

Specification of Letters Patent.

Patented June 8, 1920.

Application filed July 17, 1917. Serial No. 181,172.

To all whom it may concern:

Be it known that I, WILLIAM H. LUTZ, a citizen of the United States, residing at Philadelphia, in the county of Philadelphia and State of Pennsylvania, have invented a certain new and useful Improvement in Rug-Rolling Machines, of which the following is a specification.

The present invention relates to a machine for rolling rugs, carpets and lengths of material generally into rolls or cylindrical packages for shipment, storage or any ordinary use. An object of the invention is to provide a mechanism for automatically handling lengths of material of any kind and by which the said lengths are successively and individually formed into rolls, each being then a complete unit of compact form.

A further object of the invention is to provide a feed mechanism which operates in a predetermined manner to deliver lengths of material to a rolling and forming mechanism in accordance with the operating conditions existing in said forming mechanism.

A further object of the invention is to provide a forming mechanism whereby a length of material is accurately rolled into cylindrical form, while said mechanism automatically adjusts itself to the variation in the diameter of the growing roll and maintains a uniform pressure upon the material so that the resultant package is wound true and tight.

A further object to provide a mechanism for automatically ejecting and delivering a complete roll from the machine at the end of each winding or rolling operation.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings—

Figure 1 represents a side elevation of a material rolling machine of my invention showing the receiving end portion of the machine.

Fig. 2 represents a side elevation shown as a continuation of Fig. 1 and showing the rolling mechanism and its adjuncts.

Fig. 3 represents an elevation of the machine taken in the direction of arrow A of Fig. 2.

Fig. 4 represents an enlarged side elevation of a portion of the machine taken at the side opposite to that shown in Fig. 2.

Fig. 5 represents a section on line 5—5 of Fig. 3.

Fig. 6 represents a section on line 6—6 of Fig. 5.

Fig. 7 represents a detail in side elevation of a cam plate.

Fig. 8 represents a section on line 8—8 of Fig. 3.

Fig. 9 represents an enlarged sectional detail on line 9—9 of Fig. 8.

Fig. 10 represents a side elevation of a supporting guide plate.

Fig. 11 represents an enlarged detail of the type of movable guide-jaws employed for maintaining a suitable pressure upon the material while it is being formed into a roll.

Fig. 12 represents a sectional detail on line 12—12 of Fig. 3, showing the ejecting device.

Fig. 13 represents a section on line 13—13 of Fig. 3 showing the arrangement of the material guide-roll.

Fig. 14 represents a section on line 14—14 of Fig. 3.

Fig. 15 represents a section on line 15—15 of Fig. 14.

Fig. 16 represents an enlarged detail in plan of the power transmission for the conveyer which delivers the material to the rolling mechanism.

Fig. 17 represents an enlarged detail in side elevation of one of the cam members for controlling automatically the material engaging means.

Fig. 18 represents a side elevation of one of the adjustable journal boxes for the feed rollers.

Fig. 19 represents an end elevation of the same.

Fig. 20 represents a detail of the operating lever for the feed roller at the receiving end of the machine.

Fig. 21 represents a section on line 21—21 of Fig. 2 showing the driving means for the conveyer and the automatical release for the same.

Fig. 22 represents an enlarged side elevation of the frame for the feed rolls at the receiving end of the machine.

Fig. 23 represents a section on line 23—23 of Fig. 2 showing the conveyer track and its adjuncts.

Fig. 24 represents an enlarged detail of the type of material engaging clamp employed to feed the material to the rolling mechanism with the movement of the conveyer.

Fig. 25 represents an end elevation of the material as rolled by the machine.

1 designates generally the frame of the machine which is preferably of elongated structural form and of a length sufficient to accommodate one or more rugs or like shape of material to be rolled as required. The frame 1 is arranged to support throughout one portion a feeding mechanism for the material and at the other portion a mechanism for rolling or folding the material into a package for shipment or otherwise, so that the frame and adjuncts supported thereby may, for convenience, be divided into a receiving portion, a feeding portion and a rolling or forming portion, the latter also including, in the present instance, an ejecting or discharging means for the formed package or roll. In taking up the description of the apparatus in detail, the parts forming the above portions will be treated individually and in sequence.

At the receiving end of the machine, the frame 1 is provided with a movable table or extended platform 2 which is preferably pivoted to the frame 1 in such manner that its outer or free end may be shifted according to requirements by the control lever 3, this operation being dependent upon whether the material being fed to the table 2 is of the desired grade to be rolled or not. In the former case, the material is fed into the machine for rolling, while in the latter, the table 2 is shifted so that the poorer or rejected grade may traverse the inclined guide-plate 4 and be delivered by the feed rolls 5 to a receiving platform or truck 6 for removal, as will be understood.

The feeding mechanism is located adjacent the receiving table 2 and in position to readily engage the material delivered to it and consists of a chain driven conveyer 7 of the endless type passing about the sprockets 8 at one end and similar sprockets 9 at the opposite end. In the present instance, the conveyer sprockets 8 are mounted upon a transverse shaft 10 having bearings in the side frame 11 and which shaft also carries the lower of a pair of feed rolls 12 and 13. The roll 12 lies between the sprockets 8 and is arranged to support the material to be rolled with its opposite side edges in close proximity to the chains 7. The feed roll 13 is mounted to rotate with the shaft 14

which has its ends mounted respectively in journal boxes 15 and the latter are arranged to slide at will in yokes 16 of the frame 11. This sliding action permits the roll 13 to be moved out of its normal contacting position with the roll 12 in order to insert the end of the material and for this purpose the lever 17 is provided, which has a link connection 18 with the box 15, as will be understood. The conveyer chain is equipped at 75 suitable intervals with clamping jaws for automatically attaching the material temporarily to the conveyer, and in Fig. 24 of the drawings one of these members is shown in detail and the description thereof will be 80 understood to apply to all, since they are all of similar construction. 19 designates a member inserted as a link in the chain and having at one end a roller 20 adapted to co-operate with a track mechanism to be presently described, and at the opposite end a jaw part 21 arranged opposite to a movable jaw 22 upon a pivoted arm 23, which is carried by an extension 24 of the link member 19. The arm 23 carries a roller 25 at the 90 opposite side of the fulcrum 26 from the jaw 22, for the purpose of engaging at certain times a cam mechanism which causes the jaw 22 to be automatically opened and at other times for engaging a mechanism to 95 maintain the jaw in gripping relation with the material which it conveys. 27 designates rails located respectively at the sides of the frame 1 and in the path of movement of conveyer chains 7, each of which is provided with a recess or groove 28 forming a track for the rollers 20 and also has yieldingly mounted tracks 29 which respectively co-operate with the rollers 25 to maintain the jaws properly closed at the required time. 100 These tracks 29 are supported upon spring members 30, the tension of which is sufficient to hold the jaws gripped upon the material in the required manner. The opposite ends of the rail-bars 27, as well as the 105 tracks carried thereby, are tapered to properly direct the respective rollers 20 and 25 to the rails, as will be apparent. 31 designates cam plates secured to the respective frames 11 and so positioned with respect to 110 the conveyer chains as to locate the cam track 32 in the path of the rollers 25, whereby the jaws of the clamps are automatically opened as the conveyer makes the turn adjacent the receiving end of the machine, and consequently, the material is accurately fed between the jaws 21 and 22 of the several clamps, ready to be gripped thereby, as soon as the rolls 25 are released from the cam 32 and engage the tracks 29. The material 115 may now be carried by the conveyer mechanism to the discharge end of the conveyer where it passes between the delivery feed rolls 33 and 34, the former of which is mounted substantially similar to the feed 120

130

roller 13, while the latter is carried by the driven shaft 35. The side frames 36, in which the delivery rolls are journaled, are practically similar to the frames 11, and 5 have attached to them cam plates serving the same purpose as the cam plates 31 and which are therefore, for convenience, given the same reference numerals, since the function of the cam is to open the jaws 21 and 10 22 and release the material.

The driving means for operating the conveyer mechanism is preferably of the intermittent type for the purpose of providing rest periods coincident with the ejecting operation, in order to allow a sufficient interval of time for one rug or piece of material, when completely rolled, to be ejected before another is fed to the machine. As here shown, the mechanism for feeding the conveyer consists of chain and sprocket drives operated from the main driven shaft 37, which carries a sprocket 38 for transmitting motion to a second sprocket 39 mounted upon a stub shaft 40 carrying a mutilated 20 or segmental gear 41. This gear is arranged for meshing engagement with a similar gear 42 upon the shaft 43 and both gears are provided respectively with dwell portions 44, whereby the periods of rest are produced. The shaft 43 carries a gear 45 in mesh with pinion 46 upon a third shaft 47, which latter transmits motion to a sprocket 48 and chain 49 in order to drive the sprocket 50 from which the shaft 35 is 25 driven, to cause the conveyer to travel in the desired manner. 51 designates an adjustable idler for engaging the chain 49 and maintaining the proper tension as will be understood. The shafts 40, 43 and 47, as 30 here shown, are mounted upon an adjustable base member 52 in order to take up wear or the like as required, this action being made possible by the adjusting screws 53, which are mounted in the fixed base 54 and operating 35 against the base 52, as will be apparent. In connection with the sprocket 50, it should be noted that it is preferable to transmit movement to the shaft 35 by means other than a direct positive connection in order 40 that the variation in the feeding of the material, due to the speed increase during the rolling operation, may be properly compensated, and for that purpose the sprocket 50 is mounted loosely upon the shaft 35 and 45 carries one element 55 of a clutch, which normally engages the other clutch element 56. The element 56 while keyed, as indicated at 57 to the shaft 35, is also capable of sliding axially upon the shaft and is 50 normally maintained in clutching engagement with the part 55 by the spring 58. The latter, as will be understood, has a bearing at one end against a fixed part of the frame, while at its opposite end it seats 55 upon a follower 59, which carries the clutch

part 56. It should be noted that the angle of the clutch teeth is such as to permit the clutch to automatically release if the feeding speed of the material exceeds the driving speed of the sprocket 50.

Referring now to the rolling and forming mechanism, it will be seen from Figs. 3 and 5, that end standards 60 are provided and arranged in spaced relation and have transverse tie-bars 61 which form support for 70 a plurality of fixed castings 62, the latter forming respectively guide-plate bearings for the forming mechanism, which will be presently described. The standards 60 are in the nature of end-plates 80 each of which is provided with a plurality of bearing slots 63 of which, in the present instance, there are five, each forming a bearing and seat for a movable, as well as rotatable shaft 64, it being understood that 85 there are five such shafts to correspond to the number of end bearings and (as will be seen from Fig. 3), these shafts extend transversely of the machine in parallel relation and serve respectively to support the rolling 90 and forming devices. The shafts 64 are definitely arranged with respect to the axis of rotation of the material being rolled and are all normally equally distant from this axis and are moved simultaneously to preserve 95 the same relative arrangement. The means for thus shifting the several shafts 64 consists of two cam-plates 65 mounted respectively in the end standards 60 and of circular contour so that they may have a restricted rotary movement. It will be understood that the standards 60 are suitably cast to form circular recesses or bearings in which the respective plates 65 are located. Each of the plates 65 is provided with a 100 number of cam slots 66 to serve as guides for the respective shafts 64 and the angle of these cam slots is the same in each instance, in order to move the shafts in a corresponding manner and increase or decrease their 105 radial distance from the axis of rotation of the material. Suitable guards 67 are employed to hold the plates in position without interfering with the required rocking movement which they receive. The cam 110 plates 65 are each provided with a fixed roller 68 arranged to ride upon the surface of the respective cams 69, these cams 69 being carried upon a transverse shaft 70 and receiving motion through the following 115 120 means.

71 designates a beveled gear fixed to the shaft 70, and meshing with a like gear 72 upon the spindle 73 which also carries another beveled gear 74 meshing with a beveled gear 75 upon the stub shaft 76. This stub shaft 76 carries a worm wheel 77 driven by the worm 78 on spindle 79 which receives motion from the main shaft 37 by the beveled gears 80 and 81. It will thus be evi- 130

dent that the shaft 70 is in continuous operation, while the machine is running and the cams 69 are either rocking the cam plates to diverge the shafts 64 or are holding the cam plates in normal position. It will further be noted that the contour of the cams 69 is such as to shift the shafts 64 substantially in synchronism with the increase in the diameter of the roll of material while it is being formed, and in this connection the devices for guiding and forming the material roll will now be described. 82 designates a plurality of guide rolls mounted respectively upon the shafts 64 and so arranged that the rollers are in staggered relation, but providing an opening between them in the path of the material to allow the latter to enter the forming devices, as will be understood. In the present instance, 20 there are two sets of these guide rolls 82 though it will be understood that the number and location may be varied according to requirements without departing from the present invention. In order to more effectively guide the material by these rolls, the shafts 64 are all given a rotary movement by means of sprocket pinions 83, secured to the respective shafts and driven by the chain 84 from the sprocket 85 on stub shaft 86. 25 The shaft 86 also carries a gear 87 in mesh with a gear 88 upon the main shaft 38, as will be evident.

Referring now to the forming devices, it will be seen by reference to Fig. 8, that the 35 castings 62 are each provided with a plurality of radially arranged undercut guide-ways 89, each of which is adapted to receive one of the movable former jaws 90. As these jaws are all of similar construction, the 40 same reference numerals will be applied to all and the description confined to but one of them. The jaw 90 is suitably arranged to slide radially in the ways 89 and has a yoke-shaped inner end portion 91, which 45 forms a journal box for a freely movable bushing 92 mounted upon the bearing sleeve 93, which latter rotates upon the shaft 64. 94 designates the forming rolls removably mounted upon bearing points 95, each jaw 50 being adapted to carry a plurality of such rolls, of which, in this instance, three are employed in relatively close relation to form a substantially continuous moving surface. These rolls are adapted to contact 55 with the material to form it into a roll of cylindrical form, as will be understood. Each of the ways 89 has a slot 96 to permit the free movement of the shafts 64 and not interfere with the proper operation of those 60 parts. In assembled condition, the several jaws 90 form together a substantially complete circular bounding wall concentric with the axis of the roll of material and unbroken except for the inlet passage 97 for 65 the material. 98 designates a belt driven

by a suitable pulley 99 upon the main shaft 37, the said belt passing through the yoke portion of the jaw in contact with the movable bushing 92, then around guide rolls 100 which bring it back of the former rolls 94, 70 as will be evident from Fig. 8. Suitable counterweight rolls 101 are provided to maintain the proper tension upon the respective belts and also serves to restore the jaws to their normal position after a rolling 75 operation.

In order to remove the roll material, I have provided an automatic ejecting mechanism which becomes operative substantially at the time of the completion of the rolling 80 operation, and in the present construction engages the roll or package and passes it transversely of the machine and axially of the rolling mechanism, so that it may be readily handled and removed. For this purpose, an ejecting disk 102 is employed preferably of circular contour of less diameter than the diameter of the opening formed by the forming rollers 94, so that it may pass freely from one side of the machine to the 85 other. This disk 102 is fixed to a traveler 103 mounted for sliding movement upon two of the tie-bars 61 for convenience and the location of these tie-bars is such that the body of the traveler 103 may pass through 90 the openings 104 of the respective plates 62. It will be also noted that the opening between the guide-rolls 82 is aligned with the openings 104 and consequently, in the path of movement of the traveler 103. As here 100 shown, this traveler 103 is connected at opposite sides to the ends of a rope 105 of suitable material, which passes over guide-pulleys 106 and also about the sheaves 107, one of which is intermittently actuated, 105 as will be explained, to feed the traveler in a reciprocatory manner. The driven sheave 107 is suitably mounted for rotation with the counter-shaft 108 which has a bevel pinion 109 in mesh with a beveled gear 110 110 upon a stub shaft 111, it being understood that the ratio between the gears is properly designed for the speed and movement required. The shaft 111 is suitably journaled and carries a pinion 112 keyed or otherwise secured to rotate with it and the said pinion is located between inner and outer concentrically arranged segmental gears 113 and 114, which gears comprise the master-gear 115, which determines the direction of 115 rotation of the pinion 112 and consequently the direction of travel of the ejector. By reference to Fig. 14, it will be seen that the geared or toothed portions of the master-gear 115 are located out of alignment so that 120 when one is in mesh with the pinion 112, the other will be out of mesh and as these portions 113 and 114 engage opposite sides of the pinion 112, it is evident that the shaft 111 will first be rotated in one direction and 130

then in the other as the master-gear rotates. In order to maintain the pinion 112 properly located with respect to the gear teeth, so that it will accurately mesh, there is a 5 flanged part 116 provided as a part of the pinion 112, the outer and inner faces of which conform to the curvature of the outer and inner circumferences of the rest portion of the gears. The part 116 is provided to 10 coöperate with suitable flanges 117 concentrically arranged and spaced apart to form a track to one side of the plane of the gear portion and in which the pinion flange 116 rides as the master-gear is rotated. The 15 master-gear is keyed to the shaft 78 and is consequently continuously in operation since it is driven from the main shaft 37. The operation of the machine is as follows:

The material to be rolled is previously cut 20 to size before coming to the machine and may be in the form of a rug, a mat, a carpet or any suitable shape or material which is to be rolled as a unit and these cuts, rugs or whatever they may be, are delivered one at 25 a time, to the table 2, where there is an operator whose duty it is to separate the seconds or poorer grade of material from those which are to be delivered to the machine and rolled for shipment or use. Those which 30 are rejected by the operator are allowed to drop beneath the table 2 by moving it through the operation of lever 3 whereupon such rejected material passes down the inclined way 4 through the roll 5 and is deposited upon the waiting truck. The accepted 35 material is passed into the feed rolls 12 and 13 where its opposite side edges pass between the jaws 21 and 22 of the conveyer clamps. These clamping jaws have been 40 opened at this time by the cam tracks 32 which hold them in open position sufficiently long to permit them to properly place themselves with respect to the material and thereafter the roller 25 of the jaw 22 engages 45 the spring-pressed track 29 and the said jaw is brought to closed or gripping position upon the material and the latter is consequently fed forwardly with the movement of the conveyer and delivered to the rolling 50 mechanism after passing through the feed rolls 33 and 34. At this point, the clamps at opposite sides of the material successively come into contact with the second set of cams and the jaws 22 are automatically thrown 55 open so that the material is disengaged from the clamps as it passes through the feed rolls 33 and 34. The conveyer for the material is preferably operated in an intermittent manner in order to allow the ejecting mechanism 60 to discharge a completed roll and return to its normal position before another strip of material is fed into the rolling and forming mechanism. This momentary rest period of the conveyer is taken care of by the seg- 65 mental or mutilated gears 41 and 42 which

are continuously actuated by motion transmitted from the main driven shaft 37. The material passing through the rolls 33 and 34 enters the forming and rolling mechanism through the inwardly tapered opening 104 70 and at once comes into contact with the end rolls 82 of the series of guide-rolls and also with the belt driven former rolls 94, which causes the end of the material to be turned back upon itself describing a substantially 75 circular path, and after one convolution, the end of the material meets the body of the entering material after its edge has been suitably turned in and thus convolution after convolution is wound in spiral form. Nat- 80 urally, the diameter of the roll increases as the successive convolutions are added and, consequently, the tension produced upon the 85 slideable formers 90 by the counterweights 101 is overcome and the formers are forced radially away from the axis of the roll. This opening movement of the formers 90 is controlled in a positive manner by the cams 69 operating in conjunction with the cam roller 68 and as the contour of the cam is 90 definitely laid out with regard to the uniform increasing of the roller diameter, it will be evident that the cam plates 65 are so shifted as to simultaneously move the shaft 64 radially outward and thus carry the formers as well as the guide-rolls 82 radially 95 away from the axis of the roll, though still allowing the rolls 82 and formers 94 to remain in contact with the material as it is being formed into the rolls. Upon the completion of the roll, the driving means has brought the master-gear into such a position that the gear teeth 113 mesh with pinion 112 and thus transmit a movement to the sheave 107 which causes the driving rope 105 to feed 100 the traveler 103 from the right, as seen in Fig. 3, to the left and thereby push or eject the roll from the side of the machine ready for use. When the ejector has reached a position where the roll is free for removal, 105 the master-gear has rotated to a point where it is out of mesh with the gear 113 and comes into mesh with gear 114 and the latter reverses the direction of rotation of the pinion 112 and the traveler 103 therefore returns to 110 its normal position. At this time the conveyer mechanism automatically starts and delivers another length of material to the rolls and the foregoing operation is repeated. It should be noted, during the winding 115 of the material into a roll, that there is a natural tendency for the speed of the material to increase, owing to the increasing diameter of the roll and in order that this may be compensated, there is provided the 120 clutch release mechanism illustrated in Fig. 21. Under normal conditions, the spring 58 retains the member 56 in clutched relation with the member 55 and consequently the 125 conveyer moves at the same speed as the 130

sprocket 50. If, however, the rolling speed increases and exceeds the speed of the sprocket 50, the pulling tension of the material is sufficient to overcome the tension of the spring 58 and the clutch is automatically released.

What I claim is:

1. In a device of the character stated, a frame, a feeding mechanism mounted on said frame for delivering material to be rolled, driving means for said feeding mechanism, forming devices for automatically rolling the material into a package, and means for automatically releasing the feeding mechanism from the driving means under higher speed conditions than the speed of the driving means.
2. In a device of the character stated, a mechanism for forming material into a roll comprising a support, a plurality of jaws radially arranged upon said support and each adapted to slide thereon, rolls respectively carried by said jaws forming the bounding walls of a substantially circular opening, and means to yieldingly hold said jaws in normal position.
3. In a device of the character stated, a mechanism for forming material into a roll comprising a support, a plurality of jaws radially arranged upon said support and each adapted to slide thereon, rolls respectively carried by said jaws forming the bounding walls of a substantially circular opening, and means to rotate said rolls.
4. In a device of the character stated, a mechanism for forming material into a roll

comprising a support, a plurality of jaws radially arranged upon said support and each adapted to slide thereon, rolls respectively carried by said jaws forming the bounding walls of a substantially circular opening, means to rotate said rolls, and means to yieldingly hold said jaws in normal position.

5. In a device of the character stated, a mechanism for forming material into a roll comprising a support, a plurality of jaws radially arranged upon said support and each adapted to slide thereon, rolls respectively carried by said jaws forming the bounding walls of a substantially circular opening, and cam controlled means for simultaneously shifting said jaws radially of said support.

6. In a device of the character stated, a mechanism for forming material into a roll comprising a support, a plurality of jaws radially arranged upon said support and each adapted to slide thereon, rolls respectively carried by said jaws forming the bounding walls of a substantially circular opening, cam controlled means for simultaneously shifting said jaws radially of said support, and means to rotate said rolls.

7. In a machine of the character stated, the combination of a support, means including a plurality of slidable jaws for forming material into a roll, and means for yieldingly holding said jaws in operative position.

WILLIAM H. LUTZ.
